COMBINATION INTERCOMMUNICATION TELEPHONE AND SWITCH CABINET

Adolf Erwin Adler, London, England

Application June 25, 1953, Serial No. 25,649

Term of patent 7 years

(Cl. D26—14)

Fig. 1.

Fig. 2.

To all whom it may concern:

Be it known that I, Adolf Erwin Adler, a subject of the Queen of England and resident of London, W. 1, England, have invented a new, original, and ornamental Design for a Combination Intercommunication Telephone and Switch Cabinet, of which the following is a specification, reference being had to the accompanying drawing, forming part thereof.

Figure 1 is a front perspective view of a combination intercommunication telephone and switch cabinet showing my new design, and

I claim:

The ornamental design for a combination intercommunication telephone and switch cabinet, substantially as shown.
